METHOD FOR PRODUCING NITROGEN FROM INTERNAL-COMBUSTION ENGINE EXHAUST GASES

Eric L. Pridonoff, Alhambra, and Arthur J. Schneider, Pasadena, Calif., assignors to Aerojet Engineering Corporation, Azusa, Calif., a corporation of Delaware

Application June 30, 1944, Serial No. 543,042

2 Claims. (Cl. 23—220)

1

This invention relates to inert gas generators and has for its object to produce an inert gas under high pressure.

Inert gases such as nitrogen compressed in suitable tanks are useful for supplying gas pressures. According to our invention we provide a system for producing such an inert gas under relatively high pressure, such as 2500 pounds per square inch. The system comprises an internal combustion engine, for example, a gasoline engine which burns gasoline and air. The exhaust gases of such an engine contain the nitrogen from the air together with products of combustion such as water vapor and carbon compounds. Difficulty has heretofore been experienced in producing nitrogen from an engine exhaust at such high pressure due to the corrosive effect of impurities and moisture in the gas. We have removed these impurities other than the inert nitrogen by sending the gases through a system of purifiers and dehydrators associated with a compressing system so that the gases are made sufficiently dry and pure to provide efficient production of the substantially pure nitrogen. In this way we have succeeded in removing the presence of undesirable components which might interfere with the operation by producing corrosive effects.

A feature of our invention resides in the novel arrangement for driving the compressors from the engine itself. Other features relate to the use of refrigerating coolers for producing dehydration and a related feature is the use of a dehydrator for dehydrating the gases prior to their being brought to the ultimate high pressure. A related feature is the use of a purifier comprising activated carbon.

Our invention will be better understood from the following description and accompanying sheet of drawings in which:

Fig. 1 is a schematic plan view of a complete field plant;

Fig. 2 is a perspective view of the unit with panels in raised position;

Fig. 3 is a perspective view of the unit with vertical panels dropped.

Similar numerals refer to similar parts in the drawings.

The engine 1 is an internal combustion engine, for example, of the type burning a vaporized hydrocarbon such as gasoline in air. The engine drives the multistage compressor 2 and is operated with a rather rich mixture to obtain an exhaust gas having a low content of corrosive agents. A sufficient pressure is maintained by the engine to force the exhaust gases through the various conduits and installations between the engine and the compressor.

Passing these gases through a conduit 3 into the steam boiler 7 in which their temperature is

2

considerably reduced by giving up a percentage of their heat, producing steam in the coils of the boiler. The gas then is discharged through conduit 8 into the gas reheater 9 at a temperature which may for example be around 500° F. In this reheater 9 the hot gases lose an additional amount of heat and their temperature drops somewhat, say to 472° F. approx. The gases then pass through the exhaust gas cooling coil 10 and in doing this their temperature is lowered to approximately 150° F. which varies according to the temperature of the surrounding atmosphere. The above exhaust gas cooling coil 10, reheater 9 and steam boiler 7 are cooled by a steady flow of air which is delivered by the blower 11.

The greatly cooled gas is led through conduit 12 into the refrigerated low pressure drier 15. The temperature of the dried exhaust gas drops to approximately 85° which is raised to about 105° by reheating these gases in the inert gas reheater 9. Conduit 16 leads the reheated gases into the charcoal chamber 18. A second charcoal chamber 19 is provided which enables the operator to reactivate one of the charcoal chambers while operating the other charcoal chamber. Such reactivation is performed by permitting steam as generated in the steam boiler 7 to wash out the impurities removed from the exhaust gases. The charcoal chamber containing a bed of activated carbon absorbs a large part of the nitric oxides, hydrocarbons and small traces of carbon dioxide present in the exhaust gases.

Since further drying of the exhaust gases is more easily and effectively accomplished by raising their pressure, these gases are now led through conduit 20 and an oil bath filter 20A into the low pressure cylinder 21 of the multistage gas compressor 2.

Thereupon the gas passes through an intercooler 22 into the second stage cylinder 23 where its pressure is raised to 200 pounds per square inch. The pressurized exhaust gas leaves the second stage cylinder 23 entering another intercooler 24 and flows through the inlet conduit 25 into the refrigerated high pressure drier 26. The temperature of the gas is reduced to 45° F. in the refrigerated high pressure drier 26 condensing some more of the remaining water vapors, which are removed by the water trap 28 inserted into the outlet conduit 27. For final dehydration the gases are directed through conduit 27 into the silica gel chamber 29 in which their water content is further reduced to approximately 0.01%. For the final pressurization the gas now flows through conduit 30 into the third stage cylinder 31 of the multiple stage gas compressor 2 and is forced through a third intercooler 32 into the fourth stage cylinder 33. The gas having a pressure say of 3000 pounds per square inch

leaves the fourth stage cylinder 33 and enters an aftercooler 34 in which its temperature is reduced to around 125° F., it being understood that the fluctuations of the gas temperatures are caused by the compression of the gases. The fully compressed gases are now led through conduit 35, gas filter 36 and gas conduit 37 into the gas receptacles 38 where they remain stored. An outlet conduit 39 leads the inert gas under high pressure to the filling nozzle 44 which is attached to the above conduit 39.

In this system of producing an inert gas from the exhaust gases of an internal combustion engine the above cooling may be effectuated by the insertion of a refrigerating system based on Freon as refrigerant. Such refrigerating system comprises a refrigerant compressor 45 which raises the pressure of Freon to between 90 and 120 pounds per square inch and the temperature to approximately 95° F. depending upon external air temperature. If the pressure in the discharge line 46 between the refrigerant compressor 45 and the air-cooled Freon condenser 49 exceeds 195 pounds per square inch the relief valve 43 vents the excess pressure of the discharge line 46 into the suction line 60. A discharge gage 47 indicating the pressure from the compressor is inserted between the said compressor and the relief valve 43.

The vaporized Freon is cooled to 85° F. in the Freon air-cooled refrigerant condenser 49. The Freon flows as a liquid into the refrigerant receiver 50. The liquid Freon passes from receiver 50 through conduit 51, to a T 54 which divides the stream of Freon into two branches.

One branch directing the Freon into the thermal expansion valve 55, the other branch carrying it to the expansion valve 56. The Freon is evaporated in the valve 56 and passes through coil 57 thereby cooling the exhaust gases as previously stated. Expansion valve 55 permits evaporation of Freon which is led through coil 53 thereby effectuating the cooling of the exhaust gases in the refrigerated high pressure dryer 26.

The evaporated Freon is now led into the suction conduit 60 of the refrigeration compressor 45. An evaporator pressure regulator 61 is inserted in line 60 and maintains a predetermined evaporator pressure of 25.5 pounds per square inch in the line between the expansion valves 55 and 56 respectively and the evaporator pressure regulator, regardless of sudden load changes and fluctuations in suction pressure. This pressure determines the boiling temperature of the Freon and thereby the temperature of the coils in the refrigerated low pressure and high pressure dryers is maintained at 32° F. by the evaporator pressure regulator. This is a pilot-operated piston valve maintaining a set pressure by a pilot adjustment means.

A steam system is incorporated in the system for producing an inert gas from the exhaust gases of a gasoline engine and is used to reactivate the bed of activated carbon in the charcoal chamber 18 and 19.

The steam system operates with a gear-type boiler feed water pump 70 which meters the feed water to the steam boiler 7 through conduit 71 at pressures up to 30 pounds per square inch.

Steam is generated by continuously passing 15 gallons per hour of water through the steam boiler 7 which is located in the exhaust gas conduit 3 and the heat of the exhaust gases boil the water to produce steam at 300° F. which consequently cools the exhaust gases proportionately.

Soft water for the boiler may be derived from a water softener or other source.

The water flows from the water softener tank (not shown) through conduit 71 into the steam-boiler 7 in which it is vaporized and the steam flows through conduit 71 into the steam separator 78. Excess moisture in the steam is trapped by the steam condensate separator 79 and is drained to the atmosphere.

Before the steam reaches either activated charcoal chamber 18 or 19 there is a pressure gage 81 and a relief valve 82 installed in the conduit 80. The steam flows for example into the charcoal chamber 18 below the carbon bed through valve 92. Partial condensation occurs when the steam strikes the cold metal members of the chamber. The steam removes the impurities collected by the carbon bed from the exhaust gas which are liberated by the high temperature of the steam and the condensate is drained out of the conical bottom of the chamber through the steam trap 84 after flowing through the strainer 83. The strainer 83 prevents any foreign particles to flow into the steam trap 84 which may be damaged thereby.

Conduit 85 leads the steam into the second charcoal chamber 19 through valve 93 thereby permitting alternate use of either chamber during the operation of the inert gas generator. Drain outlets 86 and 87 respectively may be shut off separately by the inserted valves 88 and 89 respectively. Pressure relief valves 90 and 91 are installed on chambers 18 and 19 respectively. The steam pressure of these chambers is thereby regulated and the relief valves will blow off when such pressure reaches 30 pounds per square inch. Each chamber has an inlet valve 92 respectively 93, which may be opened alternately for operating each chamber independently from the other chamber.

All of the above units are mounted on a frame comprising four gas receptacles 38 made of double extra strong steel pipe and having heavy head plates welded into their several ends. These tanks 45 are welded in pairs to the flanges of two channels 100 (Fig. 2) which are placed parallel to each other at a distance and are curved upward at each end, facilitating their use as skids for the entire generator. Diagonal cross members secure 50 the proper spacing of the tanks 38 and channels 100. A steel plate 102 is welded between the channels and a bit above the channel web covering the entire bottom of the frame and is curved upward in a manner which is similar to that of 55 the two channels 100, thereby providing a dirt-proof frame bottom which may act as a secondary skid and support. An angle iron frame 103 with cross members is welded to the top of the gas tanks 38. The outside gas receptacles 38a and 60 38b are provided with drain valves 95 and 96 (Fig. 1) respectively.

A plurality of posts 104 are welded to the angle iron frame 103 supporting a roof 105. The roof is made of angle iron with channel cross members 65 having a sheet iron plate welded thereto. An ample opening is provided in the roof above the exhaust gas cooling coil 10 which may be closed by a hinged door 106.

The entire sides formed by the plurality of posts 70 are enclosed by a plurality of panels 107 consisting of sheet iron welded over an angle iron frame and enclosing a thickness of insulating material. The vertical panels 107 are hinged at their top to the angle irons of the roof frame, except the horizontal panel which is second from the front on the

right side and is hinged on one side (not shown). When the generator unit is to be used each panel is swung upward and is supported in a horizontal position by two poles 108 which are hinged to the inside bottom of the panel. The support poles 5 108 are secured at the top inside of the panel when not in use.

A standard steel pipe 109 is welded between the flanges at each curved end of the two channels 100 providing towing bars. A part of the channel 10 web being removed to facilitate easier access to the towing bars.

For the purpose of lifting the generator unit, cable guides 110 respectively 111 (Fig. 3) are welded to the outside of the channels at each 15 end, and to the edge of the roof on both longitudinal sides near the center of the unit, to guide the cables when the unit is lifted.

When gasoline and air have been used in the engine, a chemical analysis of the purified compressed inert gas has shown the following composition, the proportions being percentages by weight:

	Per cent
Nitrogen (N ₂)	86
Carbon dioxide (CO ₂)	12.5
Water (H ₂ O)	.01
Carbon monoxide (CO)	1.1
Oxygen (O ₂)	.2

When desiring to produce substantially pure nitrogen the partly compressed gases leaving the intercooler 24 may be passed through conduit 25 into a small tower 25A containing sodium hydroxide. The sodium hydroxide removes the greatest part of the CO₂ contained in the gases, which then are led into the refrigerated high pressure drier 26. The remaining process is fully described on page 3 line 13.

The substantially pure nitrogen gas shows the following composition, the proportions being approximate percentages by weight:

	Per cent
Nitrogen (N ₂)	98.4
Carbon dioxide (CO ₂)	.01
Water (H ₂ O)	.01
Carbon monoxide (CO)	1.1
Oxygen (O)	.2

For the proper operation of our generator the following steps may be followed: When starting the inert gas generator, the blower 11 is started first; the boiler feed water pump is engaged next and the gasoline engine 1 is started after its clutch has been thrown out disengaging the multistage compressor 2. Engine may be left running for five minutes.

After engaging the multistage compressor the bleed valve may be opened for a short time, thus relieving the discharge line 35 and the filter 37 whereupon the bleed valve may be closed.

It takes about 45 minutes for the gas compressor to build up the gas receptacle pressure to 3000 pounds per square inch. When this pressure is reached:

1. The speed of the gasoline engine should be reduced until the production of inert gas is equal to the rate of use, or
2. Sufficient gas should be bled off through the bleeder valve 35a to prevent the pressure from rising further, or
3. The gas compressor should be stopped by

disengaging the clutch. In such a case the refrigeration compressor should be stopped until the gas compressor is started again.

From the foregoing description and the attached sheets of drawings it can be seen that we have provided a positive inert gas generator useful for field operation.

By reason of the use of the activated carbon chambers 18 and 19 substances which have been especially harmful in producing corrosive effects, particularly the oxides of nitrogen, are removed. Since even small traces of nitrogen oxides tend to produce corrosion in the presence of moisture, especially at the high pressures to which the nitrogen is ultimately raised, the subsequent efficient dehydration in the refrigerating coolers 57 and 53 is especially salutary. By reason of the low temperatures to which they cool the gases passing through them they separate most of the moisture from the gas. The use of the silica gel chamber 29 before the gases enter the final high compression stages of the compressors is of especial advantage in removing the last harmful traces of the water, which if present with oxides of nitrogen in the high compression stages would produce corrosion. By reason of the combination and correlation of the stages of purification, dehydration and compression in the manner disclosed herein we have produced a simple and effective pure nitrogen generating system of sufficiently small weight and bulk to enable it to be incorporated into a single portable unit.

We claim:

1. In the production of nitrogen gas at pressures in excess of 500 pounds per square inch from the exhaust gases of an internal combustion engine containing a large proportion of nitrogen together with oxides of nitrogen and water vapor and involving the cooling of the gas to condense water vapor, the removal of the water thus condensed, the treatment of the residual gas with activated carbon to remove oxides of nitrogen, and the compression of the gas thus purified in a multiplicity of stages with cooling between stages, the improvement which comprises treating the gas in compressed state after the last cooling stage and immediately prior to the final compression stage with silica gel to reduce its water content and thereby reduce the corrosive effect of any residual oxides of nitrogen in the gas.

2. In the production of nitrogen gas at pressures in excess of 500 pounds per square inch from the exhaust gases of an internal combustion engine containing a large proportion of nitrogen together with oxides of nitrogen and water vapor and involving the cooling of the gas to condense water vapor, the removal of the water thus condensed, the treatment of the residual gas with activated carbon to remove oxides of nitrogen, and the compression of the gas thus purified in a multiplicity of stages with cooling between stages, the improvement which comprises treating the gas in compressed state after the last cooling stage and immediately prior to the final compression stage with silica gel until its water content is less than .01%, whereby the corrosive effect of residual oxides of nitrogen in the gas is inhibited.
